ASPHALT SHINGLE

Otto J. Kuhn, Syracuse, N. Y.

Application May 27, 1932, Serial No. 613,902
Renewed February 3, 1937

8 Claims. (Cl. 108—7)

This invention relates to certain improvements in shingles of the class set forth in my pending application Serial No. 550,489 filed July 13, 1931, and refers more particularly to the means for determining the amount of overlap and alinement of the shingles during progressive laying of the same.

The main object is to enable these shingles to be cut from the sheets without waste and in such manner that a greater number of squares may be more accurately laid in a given period of time and with less labor than has heretofore been practised.

One of the specific objects is to provide one corner of each shingle with an underfolding flap having a nailing tab projecting beyond the adjacent end edge of the shingle so that it may be nailed to a supporting surface without nailing through the body of the shingle and thus permit the end of an adjacent shingle to be easily inserted between the flap and main body to be firmly held in place by the fold of the flap.

Other objects and uses will be brought out in the following description.

In the drawing:—

Figure 1 is a face view of a portion of a roof or siding with a number of my improved shingles applied thereto.

Figure 2 is a plan on a reduced scale of a portion of a sheet from which the shingles are cut, showing the manner of cutting the same without waste.

Figure 3 is an enlarged sectional view taken on line 3—3, Figure 1.

Figure 4 is a perspective view of a portion of the roof or siding and several of the shingles, partly broken away, applied thereto.

Figure 5 is a reduced plan of one of the shingles after being cut from the sheet and before the flap is folded under the body.

In order that the invention may be clearly understood, I have shown a portion of the roof or siding A to which the shingles are to be applied, as provided with a layer 1 of water impervious paper, asphaltum or any other suitable material to serve as a backing for the shingles and thereby to assist in rendering the roof or siding water and weatherproof.

The shingle forming the subject matter of this invention is preferably made of pliable waterproof material such as a composition of asphalt, felt, or other equivalent materials, thoroughly fabricated to form a flat sheet of uniform thickness which is usually provided with an outer layer of fine gravel or equivalent material per-

manently incorporated therein to better resist wear.

These shingles are of uniform size and shape and are adapted to be laid by what is commonly known as the "Dutch lap" method in which the adjacent ends of each course overlap one upon the other.

Each shingle comprises a substantially rectangular main body 2 having one corner, in this instance the lower right hand corner, provided with an offset extension flap 3 adapted to be folded at 3' along the adjacent longitudinal edge of and under the main body parallel with the longitudinal center thereof to the position indicated by dotted lines in Figure 5 and by full lines 15 in Figures 1, 3 and 4.

The flap 3 is somewhat triangular and of approximately the length of the end overlap required and has its free end provided with a nailing tab 4 projecting beyond the adjacent end edge of the main body when folded thereunder so that a nail may be driven therethrough and into the underlying support for holding the shingle thereon without passing through the main body of the shingle.

The adjacent end edge of the main body 2 is provided with a recess 5 the same distance from the folding line 3' as the tab and preferably complementary thereto so that when the flap 3 is folded under the main body the tab 4 will register with the recess 5, thereby facilitating the driving of the nail through the tab and at the same time bringing the nail as closely as possible to the adjacent edge of the shingle.

The opposite corner of the same end of the shingle is provided with a recess 6 which is complementary to the flap 3 and both determine the amount of overlap upon the end of the next adjacent shingle of the same course and also the minimum overlap of the shingles of the next course.

The inner edge 3'' of the flap 3 and corresponding wall of the recess 6 are disposed diagonally to the longitudinal center of the shingle and their corresponding inner ends constitute markers or indicia 7 and 7' with which the end edge of the next adjacent shingle of the same course is registered to additionally determine the amount of end overlap of the shingles of the same course, one upon the other, and thereby assuring perfect alinement of the shingles of the same course without pre-marking the support upon which the shingles are placed.

The lower end wall 6' of the recess 6 constitutes a marker or indicia with which the lower edge 55

of the shingles of the next super-posed course is adapted to register and incidentally determines the minimum overlap of the shingles of the next course to facilitate the proper alining of the lower edges of the several courses without previous marking the support upon which the shingles are laid.

The tab 4 and portion of the main body of the shingle adjacent the recess 6 are provided with 10 nail holes 8 and 8' through which nails a' may be driven into the underlying support to firmly hold the adjacent end of the shingle in place.

It will be noted, however, that the nail hole 8' of each shingle is located some distance from 15 and between the shoulder 7' and end edge of the shingle and also between and in spaced relation to the shoulders 6' and 7'.

When the shingle is placed in operative position upon its support, a nail a is driven through 20 the hole 8 in the tab 4 to firmly hold the corresponding end of the shingle in place after which the next adjacent shingle is inserted endwise from the right hand toward the left hand into the fold between the flap 3 and main body over the 25 head of the nail a which was previously driven through the tab 4 and until the end edge of the underlying shingle has registered with the markers or indicia 7 and 7' whereupon an additional nail is driven through the hole 8' and underlying 30 portion of the next adjacent shingle and into the underlying support, thereby securing the overlapping portions of the shingles to each other and to said support.

When laying the shingles of the next super-posed course, their lower edges will be brought 35 into approximate registration (with slight overlap) with the marker or indicia 6', thereby covering the heads of the nails a' which were driven through the holes 8'.

As a further means for determining the 40 amount of end overlap of the shingles of the same course, the left hand end of the lower lengthwise edge of each shingle is provided with a relatively shallow recess 9, while the corresponding end of the upper edge is provided with 45 a complementary projection 9', the length of the recess 9 and projection 9' being approximately equal to the length of the fold of the flap 3 and recess 6.

The recess 9 and opposite complementary projection 9' are relatively shallow transversely but 50 parallel with the longitudinal center of the shingle, thus forming end shoulders 10 and 10' which serve as markers or indicia to determine the 55 amount of lap under the adjacent end of the next left hand shingle of the same course.

It will be observed upon reference to Figure 5 55 that the folded line 3' for the flap is in approximate alinement with the lower edge of the main body of the shingle and that owing to the nature of the material of which the shingle is made, the fold will be more or less semi-circular in cross section and, therefore, the inner face of the fold will be slightly inside of the lower edge 60 of the main body of the shingle, while the outer edge of the fold will be slightly beyond the lower edge of said main body, as shown in Figures 1 and 4 and in order that the shingles of the same course may be in exact alinement, the left hand 65 end of the lower edge is formed with a recess 9 previously explained, to compensate for the inward projection of the inner face of the fold of the flap 3.

It is, therefore, evident that when the next 70 right hand shingle is inserted into the fold of the

flap 3, its shoulder 10 will engage the right hand end of the fold and thereby limit the amount of underlap of said right hand shingle while at the same time the left hand end of the next adjacent shingle will be brought into approximate registration with the shoulder 7', thereby assuring at a glance the alinement of the shingles of the same course without pre-marking of the supports upon which the shingles are placed.

The shingles are usually laid in horizontal 10 courses from the bottom upward beginning at the left hand side of the roof or siding with each course, the lower course being laid first.

That is, the left hand shingle of the lower 15 course is first placed in operative position upon the upper surface of the covering 1 of the support A and is then secured in place by driving a nail therethrough to tab 4 into the underlying support, it being understood that care will be taken to arrange the first shingle in proper horizontal and vertical position and that in addition to the nail a driven through the upper left hand corner of the first shingle above the lower edge of the next super-posed course, to assist in holding the shingle in its proper position.

When the first shingle is properly secured in operative position, the next right hand shingle of the same course will be inserted between the underfolded flap 3 and main body until the left hand end edge of the second shingle is registered 30 respectively with the shoulders 7 and 7' at which time the shoulder 10 of the second shingle will have been brought into engagement with the right hand end of the fold of the first shingle, whereupon a nail will be driven through the tab 4 of 35 the second shingle and an additional nail will be driven through the hole 8' of the first shingle and thence through the underlying portion of the second shingle into the support A, thus securing the second shingle in place.

This operation is repeated until the first course of shingles is laid with the assurance that each shingle will be held in place by at least two nails and that each shingle will be additionally locked to the underlying portion of the next adjacent 45 shingle by means of the underfolding flap 3 which has been previously nailed to the underlying support.

The first left hand shingle of the second course is then placed in operative position upon the underlying support with its lower edge overlapping any selected distance upon the upper portion of the first shingle of the first course, and its right hand edge registering with the shoulder 10 of the 50 underlying shingle of the first course.

A nail will then be driven through the tab 4 of the first shingle of the second course and another nail a' through the upper left hand corner of the same shingle above the upper edge of the underlying shingle of the first course.

Now, having established the position of the second course relatively to the first course, the second course will be laid in the manner described for the first course and each succeeding course may be laid in like manner until the work is 65 completed.

Under ordinary conditions, the amount of vertical overlap of succeeding courses of shingles may be gauged approximately by the depth of the recesses 6. That is, the overlap must be at least 70 the depth of the recesses but may be more if desired to reduce the area of exposure of the several courses.

These shingles are usually cut without waste from a sheet of conventional roofing material of 75

the character described, as shown in Figure 2 in which the complementary flaps 3 and recesses 6, as well as the complementary tabs 4 and recesses 5 are clearly shown.

5 The cutting operation may be performed by any suitable dies under rolling or direct pressure not necessary to herein illustrate or describe for the reason that the cutting machine forms no part of this invention.

10 It will be evident from the drawing and description that each shingle will be held in place by at least three nails *a*, *a'* and *a''*, in addition to the underfolded flap 3 and that the end overlap of the shingles of each course is visually determined by the marks or shoulders 7 and 7' or 10 and 10' so that the amount of overlap of the shingles of succeeding courses may be varied at will with the assurance that the shingles of each course will be automatically aligned by reason of the 15 alinement of the left hand end of each shingle with said marks or shoulders without previously marking any lines upon the roof or siding, thus permitting a given area to be covered in less time, labor and expense than has heretofore been practiced.

What I claim is:

1. A roofing construction comprising shingles laid in courses, the adjacent ends of the shingles of each course being arranged in lapping relation and the adjacent lengthwise edges of the shingles of the several courses being also arranged in lapping relation, each of said shingles being substantially flat and having a portion thereof folded under the main body so that the surface constituting the reverse side of said main body forms the top side of said under-folded portion, the main body of the shingle and said under-folded portion being so constructed and arranged that a part of said reversed top side of said under-folded portion is exposed for receiving a nail when the shingle is lying flat on the roof with the under-folded portion of the shingle in under-folded position, and said shingles being laid so that each shingle has a portion thereof having a flat level surface lying in the pocket formed between the main body and the under-folded portion of the adjacent shingle.

2. A roofing construction comprising shingles laid in courses, the adjacent ends of the shingles of each course being arranged in lapping relation and the adjacent lengthwise edges of the shingles of the several courses being also arranged in lapping relation, each of said shingles being made of pliable water-proof material being substantially flat and having a portion thereof permanently folded under the main body during the process of manufacture so that the surface constituting the reverse side of said main body forms the top side of said under-folded portion, the main body of the shingle and said under-folded portion of the shingle being so constructed and arranged that a part of said reversed top side of said under-folded portion is exposed for receiving a nail when the shingle is lying flat on the roof with the under-folded portion of the shingle in under-folded position, and said under-folded portion being also so constructed and arranged with relation to the main body that when a nail has been driven in the exposed part of a shingle the next adjacent shingle may be slid sidewardly into the pocket formed between the main body and the under-folded part of the first shingle, the portion of said next adjacent shingle which lies in the pocket being flat.

75 3. A roofing construction comprising shingles

laid in courses, the adjacent ends of the shingles of each course being arranged in lapping relation, and the adjacent lengthwise edges of the shingles of the several courses being also arranged in lapping relation, each of said shingles being made of pliable water-proof material and being substantially flat and having a part originally projecting below the butt edge thereof, said part being folded under the main body along said butt edge so that a portion thereof extends beyond the adjacent end edge of the main body to form a nailing tab, and said shingles being laid so that each shingle has a single thickness of material lying in the pocket formed between the main body and the under-folded portion of the adjacent shingle.

4. A roofing construction comprising shingles laid in courses, the adjacent ends of the shingles of each course being arranged in lapping relation, and the adjacent lengthwise edges of the shingles of the several courses being also arranged in lapping relation, each of said shingles being made of pliable water-proof material and being substantially flat and having a part originally projecting below the butt edge at only one side thereof and also projecting beyond the main body of the shingle at said side, said part being folded under the main body along said butt edge so that a portion thereof extends beyond the adjacent end edge of the main body to form a nailing tab, and said shingles being laid so that each shingle has a single thickness of material lying in the pocket formed between the main body and the under-folded portion of the adjacent shingle.

5. A roofing construction comprising shingles laid in courses, the adjacent ends of the shingles of each course being arranged in lapping relation and the adjacent lengthwise edges of the shingles of the several courses being also arranged in lapping relation, each of said shingles being made of pliable water-proof material and being substantially flat and having a part originally projecting below the butt edge at only one side thereof, said part being permanently pre-folded under the main body along said butt edge prior to assembly of the shingles, said main body having a portion cut out therefrom to expose a portion of the under-folded part for receiving a nail, and said shingles being laid so that each shingle has a single thickness of material lying in the pocket formed between the main body and the under-folded portion of the adjacent shingle.

6. A roofing construction comprising shingles laid in courses, the adjacent ends of the shingles of each course being arranged in lapping relation, and the adjacent lengthwise edges of the shingles of the several courses being also arranged in lapping relation, each of said shingles being substantially flat and having a portion permanently folded under the main body during the process of manufacture so that the surface constituting the reverse side of said main body forms the top side of said under-folded portion and projecting sidewardly beyond the right side edge of said main body and adapted to receive a nail, and said shingles being laid from left to right by laying the first shingle and inserting a nail in the projecting portion thereof and then sliding a second shingle from right to left between the main body of the first shingle and the under-folded portion thereof so that the shingles lie in lapping relation.

7. A roofing construction comprising shingles

laid in courses, the adjacent ends of the shingles of each course being arranged in lapping relation, and the adjacent lengthwise edges of the shingles of the several courses being also arranged in lapping relation, each of said shingles being substantially flat and having a portion thereof projecting from and below the butt edge thereof and projecting sidewardly beyond the right hand corner thereof and also having a corresponding portion cut out from the upper right hand corner thereof whereby a plurality of shingles may be cut from a single sheet of material substantially without waste, said projecting portion being permanently pre-folded under the main body prior to assembly of the shingles and having a portion projecting beyond the right hand side edge of the main body to form a nailing tab, and said shingles being laid from left to right by laying the first shingle and inserting a nail in said nailing tab and then sliding a second shingle from right to left between the main body of the first shingle and the under-folded portion thereof so that the shingles lie in lapping relation.

8. A roofing construction comprising shingles laid in courses, the adjacent ends of the shingles of each course being arranged in lapping relation, and the adjacent lengthwise edges of the shingles of the several courses being also arranged in lapping relation, each of said shingles comprising a substantially flat body of flexible weather-resistant material, and having a part originally projecting below the butt edge thereof, said part being folded under the main body along said butt edge so that a portion thereof extends beyond the adjacent end edge of the main body to form a nailing tab, and said body having its butt edge indented, at a point remote from the underfolded part, and said shingles being laid so that each shingle has a portion of its body lying in the pocket formed between the main body and the underfolded portion of the adjacent shingle, and with its said indented butt edge portion nesting in the fold. 10 15 20

OTTO J. KUHN.
